Primary Examiner — Marcus Jackson*(74) Attorney, Agent, or Firm* — Fay Sharpe LLP**CLAIM**

The ornamental design for a light emitting diode (LED)-based light bulb, as shown and described.

DESCRIPTION

FIG. 1 is a perspective view of a light emitting diode (LED)-based light bulb;

FIG. 2 is a side plan view of the design of FIG. 1;

FIG. 3 is a top plan view of the design of FIG. 1; and,

FIG. 4 is a bottom plan view of the design of FIG. 1.

Any broken line illustrations in the drawings are not part of the design sought to be patented.
